UNITED STATES PATENT OFFICE.

ALFRED W. COTHEY, OF CLEVELAND, OHIO, ASSIGNOR TO THE EMPIRE PHONO PARTS COMPANY, OF CLEVELAND, OHIO, A CORPORATION OF OHIO.

RADIO AND TONE-ARM ATTACHMENT FOR PHONOGRAHS.

Application filed May 28, 1924. Serial No. 716,405.

This invention relates to a radio tone arm attachment for phonographs and has for its object to provide means whereby the sound amplifier of the phonographs may be employed either with the sound reproducing means of the phonograph or of a radio receiving set.

More particularly it is the object of the invention to provide an attachment in which direct communication may be established between the sound box or other sound amplifying means of the phonograph and either the tone arm of the phonograph or the microphone or other sound reproducing means of the radio receiving set.

With the above and other objects in view the invention may be said to comprise the device illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a sectional elevation showing the attachment applied to a phonograph; Fig. 2 is a plan view of the attachment, the body portion of which is shown in section; Fig. 3 is a section on line 3-3 of Fig. 2; Fig. 4 is a plan view of the tubular extension to which the radio attachment is secured.

Referring to the accompanying drawings, the sound box of the phonograph is indicated at 1, the turntable mounted on the sound box which carries the record is indicated at 2 and the elbow 3 through which communication is established between the tone arm and the sound box is shown attached to the top of the box at one side of the turntable 2. The tone arm carrying attachment includes a tubular member 4 which has its inner end detachably fitted within the upper end of the elbow 3, the member 4 being provided with a circumferential shoulder 5 which engages the end of the elbow and positions the attachment. The member 4 is T-shaped and has a tubular extension 6 extending laterally therefrom, the sectional tone arm 7 being swiveled to the extension 6. The extension 6 opens into the interior of the member 4 and the hollow tone arm 7 has its inner end portion fitting within the extension 6 and rotatable

therein. The tone arm is held in place in the extension 6 and its turning movement is limited by means of the pin 8 fixed to the wall of the extension 6 and projecting inwardly through a circumferentially extending slot 9 in the portion of the tone arm fitting within the extension 6. The outer end of the tone arm 7 carries the sound reproducing member 10 which has a needle 11 engageable with the record on the turntable 2.

The outer end of the member 4 is open and rotatably fitting within the member 4 is a tubular extension 12 which is held in place in the tubular member 4 and allowed a limited rotary movement by a pin 13 carried by the wall of the tubular member 4 and projecting inwardly therefrom into a slot 14 extending circumferentially of the wall of the tubular member 12. The tubular member 12 has an opening 15 in its wall which is of the same size as the opening between the tubular member 4 and its lateral extension 6 and the rotary movement of the tubular member 12 is such that the opening 15 may be shifted from a position in registry with the opening leading to the extension 6 or entirely clear of said opening. When the tubular member 12 is in one position communication will be established between the tubular member 4 and the hollow tone arm 7 and when the tubular member 12 is turned in the opposite direction, the amount permitted by the slot 14 the opening 15 will be out of registry with the opening in the wall of the tubular member 4 and the hollow tone arm 7 will be cut off from the member 4 and from the sound box of the phonograph. The tubular extension 12 is open ended and has a reduced outer end 16 adapted to receive a radio microphone attachment 17 or other sound reproducing means of the radio receiving set.

When the phonograph is in use the extension 12 will be so positioned that the opening 15 thereof registers with the opening from the tone arm into the section 4 so that the sounds reproduced from the record are transmitted through the tone arm, the member 4 and elbow 3 into the sound box 1. When it is desired to employ the sound amplifying means of the phonograph in connection with the radio receiving set, the tubular extension 12 will be turned to the position in which the tone arm is cut off from

the sound box and the sounds emitted from the microphone 17 or other sound reproducing means of the radio receiving set will be transmitted directly through the attachment into the sound box 1.

Having described my invention, I claim—

1. A radio and tone arm attachment for phonographs comprising a tubular member having open ends, one of which is adapted to 10 be placed in communication with the sound amplifier of a phonograph, said tubular member having an opening in its wall, a hollow tone arm carried by the tubular member and communicating therewith through said 15 opening, and a tubular extension having its inner end extending into the tubular member and movable therein and its outer end adapted to receive a radio sound reproducing attachment, said tubular extension having an 20 opening in its wall adapted to be moved into and out of registry with the opening in the tubular member.

2. A radio and tone arm attachment for phonographs comprising a tubular member 25 having open ends, one of which is adapted to be placed in communication with the sound amplifier of a phonograph, said tubular member having an opening in its wall, a hollow tone arm carried by the tubular member 30 and communicating therewith through the opening, and a tubular extension having a part fitting within the tubular member and

having an opening in its wall whereby the extension may be turned to open or close the opening, said tubular extension being adapted to receive a radio sound reproducing attachment. 35

3. A radio and tone arm attachment for phonographs comprising a tubular member having open ends, one of which is adapted to 40 be placed in communication with the sound amplifier of a phonograph, a hollow tone arm carried by the tubular member and communicating with the tubular member through an opening in its wall and a tubular extension movably mounted in said tubular member, said tubular extension having a part adapted to open and close said opening. 45

4. A radio and tone arm attachment comprising interfitting tubes one having a rotative movement within the other, the outer tube having an opening in its wall and the inner tube having an opening adapted to be moved into and out of registry with the opening in the outer tube, and a hollow tone 50 arm carried by the outer tube and communicating with the opening of said outer tube, one of said tubes being adapted to be placed in communication with the sound amplifier of a phonograph and the other to receive 55 a radio sound reproducing attachment.

In testimony whereof, I hereunto affix my signature.

ALFRED W. COTHEY.
